UNITED STATES PATENT OFFICE.

CLEMMA R. RANEY, OF CHICAGO, ILLINOIS, ASSIGNOR TO INTERNATIONAL HARVESTER COMPANY OF NEW JERSEY, A CORPORATION OF NEW JERSEY.

ADJUSTING MECHANISM FOR SHOCKING-MACHINES.

1,239,621.

Specification of Letters Patent. Patented Sept. 11, 1917.

Application filed April 28, 1917. Serial No. 165,217.

To all whom it may concern:

Be it known that I, CLEMMA R. RANEY, a citizen of the United States, residing at Chicago, in the county of Cook and State of Illinois, have invented certain new and useful Improvements in Adjusting Mechanism for Shocking-Machines, of which the following is a full, clear, and exact specification.

My invention relates to adjusting mechanism for shocking machines.

In order that a shocker of the Raney type may operate successfully and do its best work in the field under varying grain conditions, it has been found that a certain constant relation must be maintained between the binding mechanism and the binder deck, between the sheaf delivery fork of the shocker and the binder, and between the cradle of the shocker and the ground.

Let us suppose that the shocker has been operating in short grain and it is desired to shock long grain. In changing from one condition to the other, it is necessary that the binding mechanism be adjusted relative to the binder deck in order that the band may be properly placed on the sheaves and be substantially equally spaced from the butts and heads thereof. It is also necessary that the sheaf delivery fork of the shocker be adjusted relative to the binder in order that the sheaf may be properly positioned on the fork for delivery to the sheaf receiving cradle, and in changing from short to long grain, it is necessary to lengthen the distance between the body of the shocker frame and the binder.

When this distance is lengthened, the sheaves will be so positioned on the delivery fork that when delivered to the cradle they will project a greater distance through the end tines of the cradle, and if the cradle were not vertically adjusted to compensate for this, the butts of the sheaves would prematurely strike the ground and the shock would not be properly set up in the field, but would lean forwardly, and if conditions were extreme, would be deposited prostrate upon the ground.

To remedy these conditions, I have devised my present invention, the object of which is to provide means for simultaneously making these three adjustments, namely, adjusting the binding mechanism relative to the binder deck, adjusting the sheaf delivery fork and shocker relative to

the binder, and adjusting the shocker cradle relative to the ground. The construction has been so devised that as the shocker is adjusted longitudinally with respect to the binder, it will also be vertically adjusted, the dimensions of the various parts being so planned that the vertical adjustment compensates in each case for the longitudinal adjustment.

A further object is to provide means for longitudinally adjusting the shocker independently of the simultaneous vertical and longitudinal adjustment, whereby any required longitudinal adjustment of the shocker relative to the binder may be obtained regardless of the height to which the shocker is adjusted.

In the accompanying drawings, wherein I have illustrated one embodiment of my invention,

Figure 1 is a top plan view of the Raney type shocker having my improved adjusting mechanism thereon;

Fig. 2 is a side elevation of Fig. 1, showing also the position of the binding mechanism relative to the shocker;

Fig. 3 is a rear elevation of the structure shown in Fig. 1;

Fig. 4 is an enlarged detail of the mechanism for vertically adjusting the shocker frame; and

Fig. 5 is a diagrammatic side elevation showing the three adjustments and the mechanism for accomplishing these adjustments.

The shocker illustrated is the well known Raney type and comprises a U-shaped frame 10 carried by wheels 11 and provided with a forwardly projecting supporting tongue 12 which is slidably supported at 13 on a laterally projecting supporting pipe 14 carried by the binder. The shocker is also provided with the usual sheaf delivery fork 15 pivoted at 16 to the shaft 17 carried by the frame and reciprocable in a fore and aft direction to deliver the sheaves received from the binding mechanism to the forwardly and rearwardly tiltable shocker cradle 18 pivoted at 19 to the main frame and provided with the usual end gate comprised of a pipe 20 and upstanding tines 21. The means for vertically adjusting the shocker frame will first be described.

The wheels 11 are carried by shafts 22

which project laterally from the lower ends of vertical standards or posts 23 having secured to their upper ends bracket members 24. The frame of the shocker has secured thereto laterally and upwardly projecting frame members 25 provided with journals 26 vertically slidable on the standards 23, and the members 25 are slidable at their upper ends through the brackets 24. These frame members 25 are formed of channel iron and the flanges thereof are slidable in suitably formed slots in the bracket members 24, as illustrated in the plan view in Fig. 1. The frame members 25 are provided at their upper ends with the angular brackets 26 rigidly secured to said members and provided with journals 27 in the laterally projecting portions thereof. A crank 28 is journaled in each of these angular brackets and has secured thereto below the bracket, a collar 29 which prevents any relative movement between the crank 28 and the bracket 26. This crank 28 has integral therewith a vertical screw 30 which is threaded in a screw-threaded aperture 31 of the bracket 24. From the above description it will be seen that as the crank 28 is turned, the standard 23 being fixed, the bracket 26, frame member 25, and the shocker frame to which the frame member is secured, will be vertically adjusted. Additional brace members 32 are secured to the frame members 25 and to the shocker frame, the front brace 32 being secured to a laterally and outwardly inclined member 33 which forms a part of the shocker frame. For the purpose of connecting the vertical adjusting mechanism with the longitudinal adjusting mechanism for the shocker, I have provided a bell crank lever 34 made up of arms 35, 36 connected by a brace 37 and pivoted to a pin 38 projecting laterally from the frame member 33. This bell crank lever is slotted at its rear end, as shown at 39, and projecting through this slot is a laterally extending pin 40 secured to the bracket 24. As clearly shown in Fig. 3, the bell crank 34 is inclined to the vertical, and at its lower end is provided with a downwardly projecting portion 41 which is guided in its longitudinal movement in a slot 42 formed in a bracket 43 secured to the shocker frame. Intermediate its pivot and its lower end, the arm 36 of the bell crank is provided with a circular journal bearing 44, in which is journaled a pipe 45 which is secured to the bell crank by means of a link 46. This pipe is journaled at its other end to a seat post 47 of the binder and carries a vertical lever 48 for rotating the pipe for a purpose hereinafter described. The pipe 45 is provided adjacent the shocker with a downwardly projecting crank arm 49 which is connected by a link 50 to the laterally projecting supporting pipe 14 on the binder.

A portion of the binding mechanism is shown in Fig. 2 and comprises a needle 51 which, with its co-operating binding mechanism, is longitudinally adjustable on the binder supporting pipe 52 in a manner well known in the art. The binding mechanism including the needle 51 is connected by means of a link 53 to the frame member 33 of the shocker, this connection being shown at 54. The operation of the three adjustments above described will now be explained.

Assuming that the parts are in the position shown in full lines in the drawings, and that in this position they are adjusted to operate on short grain, if it is desired to operate the machine in a field of long grain, the crank 28 is turned to the left, or, looking at Fig. 1, in an anti-clockwise direction. This will rotate the screw 30 and will raise the frame of the shocker, the extreme upper position being shown in dotted lines in Fig. 2. As the shocker frame and the member 25 connected thereto are raised, it will be seen that the bell crank lever 35 will be rotated about its pivot 38, since the pin 40, which is carried by the bracket 24 secured to the fixed standard 23, does not move vertically, whereas the pivot pin 38 of the bell crank is carried by the shocker frame member 33 and does move vertically. With this in mind, it will be seen that as the pivot pin 38 and bell crank are moved vertically, the rear arm 35 of the bell crank will assume a position approximately horizontal and the lower arm 36 will be rotated in a clockwise direction, assuming the position shown in dotted lines in Fig. 2, the lower end 41 of the arm 36 being positioned at the opposite end of the slot 42. As the arm 36 of the bell crank is thus rotated, the pipe 45, crank arm 49, and link 50 will also correspondingly change their position and thus the distance between the shocker frame and the binder frame will be varied correspondingly with the vertical adjustment of the shocker frame. Also as the shocker frame assumes the position in dotted lines in Fig. 2, the link 53, which connects the shocker frame with the binding mechanism, will also be adjusted and the binding mechanism will assume the position also in dotted lines in the same figure.

In addition to the simultaneous vertical and longitudinal adjustment above described, it will be noted that the shocker may be longitudinally adjusted relative to the binder independently of the vertical adjustment by means of the lever 48 mounted on the seat of the binder. As this lever is manipulated, the pipe 45 will be rotated in its bearing on the bell crank lever 34, and as this pipe is rotated, it will carry with it the crank arm 49, and by means of the link connection 50 with the supporting pipe 14 of the binder, the shocker will be longitudi-

dinarily adjusted. This relative rotation and movement of the pipe 45 with relation to the bell crank is permitted by means of the link connection 46 between these members.

5 It will thus be seen that the angular relation between the crank arm 49 on the shocker frame and the bell crank 34 can be adjusted as desired by the lever 48, and this adjusted angular relation will be maintained practically constant as the shocker is adjusted longitudinally with relation to the binder simultaneously with the adjustment of the shocker.

It will thus be seen that I have provided 15 means for simultaneously adjusting the shocker frame vertically with respect to the ground, the binding mechanism longitudinally with respect to the shocker, and the shocker frame longitudinally with respect to 20 the binder. By means of this combination adjustment, I have enabled the operator of the machine to make all the necessary adjustments occasioned by the varying lengths of grain operated upon by means of one operation. In this way I have also assured 25 the correct relative positions of the shocker and binder and the binding mechanism on the binder. By thus insuring the correct adjustment of these mechanisms, the successful 30 operation of the machine is also insured and the setting of the shocks in a correct manner is made certain.

While I have in the above specification described one embodiment of my invention, 35 it is to be understood that various modifications of the same may be made without departing from the spirit of the invention as expressed by the following claims.

What I claim as new and desire to secure 40 by Letters Patent is:

1. In combination, a binder including a binder frame and binding mechanism, a shocker, and means for simultaneously adjusting the shocker longitudinally and vertically relative to the binder and the binding mechanism longitudinally with respect to the binder frame.

2. In combination, a binder, a shocker, means for simultaneously adjusting the shocker longitudinally and vertically, and means for adjusting the shocker longitudinally independently of said last named means.

3. In combination, a binder, a shocker, means for simultaneously adjusting the shocker longitudinally and vertically with respect to the binder, and means carried by the binder for adjusting the shocker longitudinally with respect to said binder independently of the simultaneous vertical and longitudinal adjustment.

4. In combination, a binder, a shocker, and means for simultaneously adjusting said shocker vertically and longitudinally with respect to said binder, said means including

a lever pivoted to said shocker and movable with said shocker about one end as said shocker is raised and lowered.

5. In combination, a binder, a shocker, and means including a lever pivoted intermediate its ends to said shocker for simultaneously adjusting said shocker vertically and longitudinally with respect to said binder. 70

6. In combination, a binder including a binder frame and binding mechanism, a shocker, means connecting the binder and shocker and the binding mechanism and shocker for simultaneously adjusting the shocker longitudinally with respect to the binder and the binding mechanism longitudinally with respect to the binder frame, and a plurality of independently operable means for controlling said adjusting means. 75 80

7. In combination, a binder having binding mechanism thereon, a shocker frame operatively connected thereto, a swinging sheaf delivery member carried thereon, and means for simultaneously adjusting said delivery member and shocker frame relative to the binder, said shocker frame and delivery member vertically, and said binding mechanism longitudinally relative to said binder. 90

8. In combination, a binder, a wheeled truck, a shocker frame carried thereon and operatively connected to said binder, means for simultaneously adjusting said shocker frame vertically on said truck and said shocker frame and truck longitudinally with respect to said binder, and means for independently adjusting said frame and truck longitudinally with respect to said binder. 95 100

9. In combination, a binder having a binder frame and sheaf binding mechanism thereon, a wheeled truck, a shocker frame carried thereon and operatively connected to said binder, and means for simultaneously adjusting said shocker frame vertically on said truck, said shocker frame and truck longitudinally with respect to said binder, and said binding mechanism longitudinally with respect to said binder frame. 105 110

10. In combination, a binder, a wheeled truck, a shocker frame carried thereby, a bell crank lever pivoted intermediate its ends to said frame, a sliding connection between one arm of said lever and said truck, means connecting the other arm of said lever and said binder, and means for vertically adjusting said shocker frame with respect to said truck. 115

11. In combination, a binder, a wheeled truck, a shocker frame carried thereby, a bell crank lever pivoted intermediate its ends to said frame, a sliding connection between one arm of said lever and said truck, means adjustably connecting the other arm of said lever and said binder, guiding means for the lower end of said bell crank lever, 120 125 130

- and means for vertically adjusting said shocker frame with respect to said truck.
12. In combination, a binder, a wheeled truck, a shocker frame carried thereby, a bell crank lever pivoted intermediate its ends to said frame, one of the arms of said bell crank lever being held at one point against movement in a vertical plane, means for connecting the other arm of said lever to said binder, and means for adjusting said shocker frame vertically.
13. In combination, a binder, a shocker, means including a crank shaft for simultaneously adjusting said shocker longitudinally and vertically relative to said binder, means for rotating said shaft to vary the longitudinal adjustment of said shocker, and means for moving said crank shaft bodily to vary said longitudinal adjustment.
14. In combination, a binder, a shocker, a bell crank lever pivoted on said shocker, a crank shaft journaled on said lever, a crank on said shaft, operative connections between said crank and said binder, means for rotating said crank shaft, and means for tilting said lever.
15. In combination, a binder, a wheeled truck, a shocker frame carried thereby, a bell crank lever pivoted to said frame, a pin and slot connection between one arm of said bell crank lever and said truck, a crank shaft journaled in the other arm of said bell crank lever, operative connections between said crank shaft and binder, means for rotating said crank shaft, and means for tilting said bell crank lever.
16. In combination, a binder, a shocker, a bell crank lever pivoted on said shocker, a crank shaft journaled at its grainward end on said binder and at its stubbleward end on said bell crank lever, means connecting the stubbleward end of said crank shaft to said binder, means for rotating said shaft, and means for tilting said lever.
17. In combination, a binder including a frame and binding mechanism thereon, a shocker, means for adjusting said shocker vertically, and means actuated by said last mentioned means for adjusting said shocker and binding mechanism longitudinally with respect to said binder frame.
18. In combination, a binder including a frame and binding mechanism thereon, a shocker, means for adjusting said shocker vertically, and means for adjusting said shocker and binding mechanism longitudinally with respect to said binder frame and maintaining a constant proportion between the vertical movement of the shocker and the longitudinal movement of the shocker and binding mechanism.
19. In combination, a binder, a shocker, means for simultaneously adjusting said shocker vertically and longitudinally with respect to said binder, said means including a lever pivotally connected to said shocker, and means for simultaneously moving said lever and for swinging said lever about its pivot.
20. In combination, a binder, a shocker, means for simultaneously adjusting said shocker vertically and longitudinally with respect to said binder, said means including a lever pivotally connected to said shocker, and means for simultaneously adjusting said pivot vertically and for swinging said lever about its pivot.
21. In combination, a binder, a shocker, means for simultaneously adjusting said shocker vertically and longitudinally with respect to said binder, said means including a lever pivotally connected to said shocker, and means for simultaneously adjusting said pivot vertically and horizontally and for swinging said lever about its pivot.

In testimony whereof I affix my signature.

CLEMMA R. RANEY.
